UNITED STATES PATENT OFFICE

136,780

DESIGN FOR A BOTTLE OR SIMILAR ARTICLE

Anna Guérin, New York, N. Y.

Application July 27, 1942, Serial No. 107,724

Term of patent 14 years

To all whom it may concern:

Be it known that I, Anna Guérin, a citizen of France, residing in New York city, in the county and State of New York, have invented a new, original, and ornamental Design for a Bottle or Similar Article, of which the following is a specification, reference being had to the accompanying drawing, forming a part thereof.

Fig. 1 is a front perspective view of a bottle or similar articles, showing my new design.

Fig. 2 is a rear elevational view thereof.

Fig. 3 is a fragmentary front perspective view of the bottle, showing the stopper removed.

I claim:

The ornamental design for a bottle or similar article, substantially as shown.

ANNA GUÉRIN.
